LOCK.

No. 919,259.

Specification of Letters Patent.

Patented April 20, 1909.

Application filed September 24, 1907. Serial No. 394,266.

To all whom it may concern:

Be it known that I, HENRY W. SIMPSON, a citizen of the United States, residing at Ithaca, in the county of Tompkins and State of New York, have invented certain new and useful Improvements in Locks, of which the following is a specification.

This invention relates to improvements in locks, and has particular relation to barrel 10 and tumbler structures for use therein.

The invention has for its object, the provision of a barrel and tumbler construction which will permit of a rotative movement of the barrel when the tumblers have been 15 moved in a direction longitudinally of the barrel to a proper position relatively thereto.

A further object is to provide the barrel with an operating element which may act as a lock or as a bolt-operating device, depending upon the position in which it is located 20 relatively to the remaining lock or latch structure.

Other and further objects of the invention will appear as the invention is hereinafter 25 disclosed.

To these and other ends, this invention consists in the improved construction and combination of parts, hereinafter fully described, illustrated in the accompanying 30 drawings, and particularly pointed out in the appended claims.

In the drawings, in which similar reference characters indicate similar parts in each of the views, Figure 1 is a perspective view 35 showing one form of my barrel and tumbler with its casing. Fig. 2 is a plan view of the same with the casing removed, the tumblers being shown in their normal positions. Fig. 3 is a similar view showing the tumblers 40 moved to a position where the barrel may be rotated by the key. Fig. 4 is a side elevation of the parts shown in Fig. 3, and having the casing shown in section. Figs. 5, 6 and 7 are cross-sectional views taken on lines 45 5—5, 6—6 and 7—7, respectively, of Fig. 4. Fig. 8 is a vertical longitudinal sectional view of Fig. 9. Figs. 9 and 10 are detail views of the tumbler-carrying member of the 50 barrel and of one of the tumblers respectively. Fig. 11 is a detail view of a key. Fig. 12 is an end view showing a modified form, an additional number of tumblers being provided. Fig. 13 is a detail view of a key used in connection with the arrangement of tumblers shown in Fig. 12. Fig. 14

is a detail sectional view showing a modified form of arrangement of the spring forming the tumbler-support. Fig. 15 shows in plan, side and end elevations, a modified construction of barrel and tumblers. Fig. 16 shows 60 in detail views, the key used in connection with the structure shown in Fig. 15. Fig. 17 is a sectional view of a drawer lock, the barrel structure shown in Fig. 15 being in position therein. Figs. 18 and 19 are detail 65 views showing the bolt of the drawer lock in different positions.

Referring first to Figs. 1 to 11, inclusive, 30 designates a barrel casing in the form of a tube open at its ends, and having at one end 70 a recess 31 adapted to fit over a stationary part of the lock casing and by means of which the barrel is held from rotation. The casing is also provided with slits 32 extending cross-wise of the casing on opposite sides 75 thereof, said slits receiving bars 33, the slits being of sufficient depth to permit the inner faces of the bars to project within the inner periphery of the casing, the slits being located at any predetermined point in the casing, such as approximately midway of the casing length. The outer surfaces of the bars 33 are rounded to conform to the outer periphery of the casing. 35 designates the barrel which consists of the tumbler-carrying member 36 and the tumblers 37. The tumbler-carrying member will first be described. The member 36 is formed substantially as shown in Fig. 9, and is of a length approximating the length of the casing. One of its ends 38 (that opposite the key-inserting end) is circular in cross-section, and adapted to fit the interior of the casing, the relative sizes being such as to permit a relative movement of the portion 36 and the casing. Said end 38 is provided with an elongated recess 39, said recess extending axially a suitable distance and having its central portion enlarged, as shown in Fig. 9. Said recess is provided for the insertion of a 100 lengthening bar 40 (see Fig. 3) when such bar is used. Spaced from the surface of the end 38 and parallel therewith is formed a circumferential groove 41 adapted to receive the projecting end of a screw or pin 42 extending through the casing. It is to be understood, of course, that the pin 42 prevents longitudinal movement of the barrel but will permit a rotative movement.

As shown in Fig. 9, the member 36, is 110

formed with a longitudinally-extending bar 44, semi-circular in cross-section and having an area approximate half of the area of a cross-section of the end 38, the bar being of 5 a suitable length. Extending radially from the center of the flattened surface of the bar 44 is a plate 45, which also extends longitudinally of the barrel and which is of such length as to terminate at approximately the 10 free end of the bar 44, a kerf 46 being formed between the inner or central surface of the bar and the inner edge of the plate, said kerf extending inwardly a suitable distance. The bar 44 is provided with a circumferentially-extending groove 47, substantially 15 midway of its length. The plate 45 is also provided with a recess 49 corresponding in position to the groove 47 of the bar. The groove 47 and recess 49 are adapted to receive the inwardly-projecting portions of the bars 33, said bars 33 and the pin 42, heretofore described, preventing longitudinal movement of the barrel in the casing.

While the plate 45 may be formed integral with the bar 44, I may form the same 20 separate from the bar, in which case I secure the plate 45 to a plate 50, the latter being of substantially the thickness of the kerf 46, and having a width equal to the width of the 25 face of the bar 44 and a length to carry its free end to the inner end of said kerf. The plate 50 is secured to the bar 44 by a screw 51, and, if desired, a suitable pin 52 may be provided either on the plate 50 or bar 44 to 30 engage a hole in the opposing surface, such construction tending to prevent relative movement of the plate 50 on the bar 44. It will be understood of course, that if the plate 35 50 be employed, the groove 47 will be extended over its edges. Adjacent the free ends of the bar 44 and plate 45, said bar and plate have their outer peripheries provided with recesses 53 and 54, respectively, extending inwardly from the end of said parts. 40 These recesses are adapted to receive an inwardly-projecting lug 57 formed on the casing 30. The mouth of the kerf 46 is preferably rounded, as shown, and at a suitable point within the kerf, and projecting from 45 the inner face of the bar 44 is a pin 55, said pin being preferably located in alignment with the plate 45.

The end 38 of the member 36 is provided with an operating element which, in the form 50 shown in Figs. 1 to 11 is in the form of a lug or projection 56 having its outer face curved concentrically with the curvature of the end 38, the distance between the periphery of the end 38 and the periphery of the lug 56 corresponding to the thickness of the wall of the casing 30. The inner face of the lug is flat as shown at 56^b, Fig. 9, the meeting points of the inner and outer faces of the lug 56 being 55 preferably rounded. The lug 56 is normally positioned on the end 38 in approximate

alignment with the bar 44. The normal position of the lug 56 when the parts are assembled, is that shown in Fig. 4, the lug projecting from the plane of the end of the casing.

The tumblers 37, two of which are shown 70 in Figs. 1 to 11, are formed substantially as shown in Fig. 10, each having a general cross-sectional shape of a right-angled triangle, the outer side of which is rounded. These tumblers are adapted to be seated in 75 the ways formed on each side of the plate 45, and the curvature of their faces corresponds to the curvature of the inner periphery of the casing, the tumblers practically completing the circular form of the barrel. Each tumbler is provided with a circumferentially-extending groove 58 and an extended recess 59, the former to receive the bar 33, and the latter to permit of the movement of the tumbler to carry it to a position where the groove 80 58 will be in alignment with the bars 33. Each tumbler is also provided with a recess 60 adjacent its outer end, said recess corresponding with the recesses 53 and 54, and each tumbler is also provided, on its face opposing the face of the bar 44 with a pin 61. 85 To retain the tumblers in position at their outer extremes of movement, springs 62 are interposed between the end 38 and the end 90 of the tumbler. While such form of providing the tension for the tumblers is preferred, the form in Fig. 14 may be employed, in which case the tumblers are provided with suitable pins 63 adapted to engage the 95 springs which are located in recesses of the 100 bar 44. Instead of the pins 55 and 61, short bars or lugs may be employed, imparting added strength to these parts.

As will be understood by an inspection of the drawings, to permit of a relative movement of the barrel within the casing, the grooves 58 of the tumblers must be brought into alignment with the groove 47 of the bar 44. This is accomplished by the key 64 which is provided with longitudinally-extending grooves 65 arranged as shown, said grooves corresponding in position to the pins on the tumbler and on the bar 44, and being of such length that when the end of the groove for the pin 55 reaches its limit of 110 movement by having its end contact with said pin, the tumblers will have been moved, by the similar contact of each pin 61 with the end of its corresponding groove, the proper distance to carry the grooves 58 into alignment with the groove 47.

The various key changes are obtained by variations in the position of the pins 55 and 61 and in the position of the grooves 58. Obviously, the change in position of any one 115 of these elements, to the slightest degree requires a corresponding change in the key wards.

While I have shown and described the use of but two tumblers, it is obvious that a 130

greater number may be used, as shown, for instance, in Fig. 12, where the plate 45 is omitted and four tumblers 37 are employed, two opposing the inner face of the bar 44 and 5 one on each of the outer sides of the central tumblers, the side tumblers being actuated by grooves on the edges of the keys. Obviously many additional key changes may be provided by such structure.

10 In the disclosure herein made the length of the recesses 54 and 60 have no important function, excepting that the inner wall thereof must be so located as to clear the projecting lug 57, the movement described above 15 being but a rotative one only. The length of the recess 53, however, is of importance, since the edges of the bar 44 serve to limit the rotative movement of the barrel, these edges projecting into the plane of the lug 57 20 during the normal rotative movement of the barrel, thereby limiting the extreme length of rotative movement.

From this description it will be seen that I have provided a barrel and tumbler structure 25 in which the barrel substantially fills the space within the tubular barrel casing, the tumblers lying within the plane of the barrel, the entire structure within the casing being relatively movable when the tumblers have 30 been properly positioned, so that there is no requirement of the use of a casing of excessive diameter or one having a radially-extending projecting portion, nor is there a requirement of the use of relatively-stationary 35 parts lying between the barrel and its casing, the longitudinal movement of the tumblers permitting of the use of the structure described. A result similar to that described is obtained by the construction shown in 40 detail in Fig. 15, the barrel 35^a in this instance being circular in cross-section substantially throughout its length, being provided with a circumferential groove 47^a, and having a series of longitudinally-extending 45 kerfs 46^a, one of which extends diametrically while the remaining kerfs extend in directions angular with respect to the diametrically-extending kerf, and may also extend angular with respect to each other, as shown. 50 The relatively angularly-extending kerfs are each adapted to receive a tumbler 37^a, which is normally retained in a position to prevent rotation of the barrel, by springs 62^a located in expanded portions of the kerf in which 55 each tumbler is located, the relative position of the expanded portions being shown by the circles shown in the end elevation of the head 67 in Fig. 15, the expanded portions being formed by boring through the head 67, the 60 outer ends of the openings so formed being closed by suitable plugs 68.

A pin 55^a is mounted in one of the walls of the diametrical kerf 46^a and projects thereinto, and each of the tumblers has its inner 65 edge provided with a pin also projecting into

said kerf. Each of the angularly-extending kerfs extends along the barrel in the direction of the head 67 to a point approximate the head 67, although it is not absolutely essential that this length be provided, it 70 being required, however, that the tumblers may have not only a longitudinal movement to be properly positioned to permit of the rotation of the barrel, but that an additional movement may be had under the action of 75

an improper key; hence, it is advantageous that the angular kerfs extend substantially throughout the length of the barrel. The rear end of the barrel is recessed, as at 53^a, to receive a lug 57^a carried by the casing, the 80 construction being such as to permit a rotative movement within certain limits. Each of the tumblers is provided with a groove 58^a, said groove being so positioned on the tumbler that when the proper key is inserted 85 within the diametrical kerf 46^a and moved longitudinally therein, the grooves of each of the tumblers will be in alignment with the groove 47^a and thereby permit the barrel to be rotated, the bars 33^a riding in said grooves 90 when aligned.

In this instance, the barrel is shown as provided with a circular head 67, of greater diameter than the diameter of the barrel, said head being provided with a radially extending operating lug 56^a having 95 its outer portion extended in both directions to provide undercut recesses 69 which may receive the walls of an opening formed in a locking bolt structure, such as shown in Fig. 17, the ends of the overhanging portions of 100 the lug 56^a being mounted in an oval-shaped opening formed in an adjacent member of the bolt A, said members being riveted or otherwise secured together to have a common movement, the structure shown being 105 such as may be used in connection with a drawer lock, so that as the barrel is moved rotatively, the bolt will be moved into or out of engagement with a suitable keeper, depending upon the direction of movement of 110 the barrel. As the rotative movement of the latter is limited as hereinbefore described, a complete movement of the barrel will move the bolt from one extreme position to the opposite extreme position, in either of which 115 positions the lug presents its greatest length in alignment with the longitudinal axis of the locking bolt.

The operating elements (the lugs 56 and 56^a) is shown herein of special form. It is to 120 be understood, however, that the invention is not limited to a barrel having the operating element of the particular form shown in Figs. 1 or 15, since provision is made for the use of a lengthening bar 40 in case such structure is desired. However, where the operating element acts directly upon the locking mechanism or the latch-bolt mechanism 125 without the intervention of an element other than a projecting portion having its path of 130

movement adjacent to the end of the barrel, I prefer to employ an operating element located relatively to the barrel in such manner as to provide a concentric operating path of movement. Obviously, the particular shape of the element is immaterial, since the shape thereof would be controlled by the particular use to which it is put.

While I have herein shown two ways in which my invention may be formed and shown other ways in which it may be applied, it will be understood that other changes may be made in the particular form and arrangement of parts, which modifications I reserve the right to use, in so far as they may fall within the spirit and scope of the invention as expressed in the following claims:

1. In a lock, a barrel and its casing, a plurality of tumblers extending longitudinally of the barrel and movable longitudinally thereof, said tumblers normally retaining the barrel against rotative movement relative to its casing, said barrel and tumblers having surfaces facing a key-entering kerf, pins on said surfaces, and a key having longitudinally-extending grooves extending from one end thereof, said grooves adapted to receive said pins and the length of each groove being such as to cause the key, when introduced into said kerf to the limit of its movement, to position the tumblers relatively to the barrel in a manner to permit rotative movement of the barrel and tumblers.

2. In a lock, a barrel and its casing, a plurality of tumblers extending longitudinally of the barrel and movable longitudinally thereof, said tumblers normally retaining the barrel against rotative movement relative to its casing, said barrel and tumblers having surfaces facing a key-entering kerf, pins on said surfaces, and a key having longitudinally-extending grooves extending from one end thereof, said grooves terminating in an abrupt wall adapted to contact with said pins, the inserting movement of said key carrying the tumblers to a position where rotative movement of the barrel is permitted.

3. A barrel and tumbler lock-operating mechanism comprising a tubular casing, a barrel fitting within said casing and rotatively mounted therein, a plurality of tumblers lying wholly within the circumferential plane of the barrel, means carried by and fixedly positioned within the casing and permanently extending into the peripheral surface of the tumblers to normally retain the barrel from rotative movement, and a key for positioning the tumblers to permit rotation of the barrel.

4. A barrel and tumbler lock-operating mechanism comprising a tubular casing, a barrel fitting within said casing and rotatively mounted therein, a plurality of tumblers lying wholly within the circumferential plane of the barrel, means carried by and

fixedly positioned intermediate the ends of the casing and permanently extending into the peripheral surface of the tumblers to normally retain the barrel from rotative movement, and a key for positioning the tumblers to permit rotation of the barrel.

5. A barrel and tumbler lock-operating mechanism comprising a tubular casing, a barrel fitting within said casing and rotatively mounted therein, a plurality of tumblers lying wholly within the circumferential plane of the barrel, means carried by and fixedly positioned intermediate the ends of the tumblers and permanently extending into the peripheral surface of the tumblers to normally retain the barrel from rotative movement, and a key for positioning the tumblers to permit rotation of the barrel.

6. A barrel and tumbler lock-operating mechanism comprising a tubular casing, a barrel fitting within said casing and rotatively mounted therein, a plurality of tumblers lying wholly within the circumferential plane of the barrel, said tumblers being movable longitudinally of the barrel, means carried by and fixedly positioned within the casing and intermediate the ends of and permanently extending into the path of longitudinal movement of the tumblers and adapted to coöperate with the tumblers to normally retain the barrel from rotative movement; and a key for positioning the tumblers to permit rotation of the barrel.

7. A barrel and tumbler lock-operating mechanism comprising a tubular casing, a barrel fitting within said casing and rotatively mounted therein, a plurality of tumblers lying wholly within the circumferential plane of the barrel, said tumblers each having an extended recess, and also having a movement longitudinally of the barrel, means carried by and fixedly positioned within the casing and extending within the recesses of the tumblers and adapted to coöperate with the tumblers to normally retain the barrel from rotative movement, said recess and said means being of a relative size to permit longitudinal movement of the tumblers, and a key for positioning the tumblers to permit rotation of the barrel.

8. A barrel and tumbler lock-operating mechanism comprising a tubular casing, a barrel fitting within said casing and rotatively mounted therein, a plurality of tumblers lying wholly within the circumferential plane of the barrel, each of said tumblers having an extended recess and a groove extending in a direction at right angles to the direction of length of the recess, means carried by and fixedly positioned within the casing and adapted to coöperate with the tumblers to normally retain the barrel from rotative movement, said means being of a width to enter said groove of the tumblers.

- to permit rotation of the barrel and tumblers when the latter are properly positioned relative to said means, and a key for positioning the tumblers relative to said means.
- 5 9. A barrel and tumbler lock-operating mechanism comprising a tubular casing, a barrel fitting within said casing and rotatively mounted therein, a plurality of tumblers lying wholly within the circumferential 10 plane of the barrel, each of said tumblers having a movement longitudinally of the barrel, means carried by the casing and positioned intermediate the ends of and permanently extending into the tumblers 15 and coöperating therewith to normally retain the barrel against rotative movement and a key for positioning the tumblers to release the tumblers from the retaining means.
- 20 10. A barrel and tumbler lock-operating mechanism comprising a tubular casing, a barrel fitting within said casing and rotatively mounted therein, a plurality of tumblers lying wholly within the circumferential 25 plane of the barrel, said tumblers extending longitudinally of the barrel and movable in the direction of their length, means carried by and fixedly positioned intermediate the ends of and permanently extending into

the casing for positioning the barrel in the 30 casing, said means and the tumblers normally retaining the barrel against rotative movement, and a key for positioning the tumblers relative to said means for permitting rotative movement of the barrel. 35

11. A barrel and tumbler lock-operating mechanism comprising a tubular casing, a barrel fitting within said casing and rotatively mounted therein, a plurality of tumblers lying wholly within the circumferential 40 plane of the barrel, said tumblers extending longitudinally of the barrel and movable in the direction of their length, each of said tumblers having a laterally-extending groove, means carried by and fixedly positioned intermediate the ends of and permanently extending into the casing for positioning the barrel therein, said means and the tumblers normally retaining the barrel against rotative movement, and a key for moving 45 the tumblers to position said grooves in alignment with said means.

In testimony whereof I affix my signature in presence of two witnesses.

HENRY W. SIMPSON.
